DESIGN FOR A WATER BOTTLE OR SIMILAR ARTICLE

Earla M. Roberts, Lancaster, Pa., assignor to Armstrong Cork Company, Lancaster, Pa., a corporation of Pennsylvania

Application May 27, 1939, Serial No. 85,238

Term of patent 14 years

To all whom it may concern:

Be it known that I, Earla M. Roberts, a citizen of the United States, residing in Lancaster, county of Lancaster and Commonwealth of Pennsylvania, have invented a new, original, and ornamental Design for Water Bottles or Similar Articles, of which the following is a specification, reference being had to the accompanying drawing, forming a part thereof, in which bottle or similar article embodying my new design.

The opposite side of the water bottle from that shown in the drawing has substantially the same appearance as the side illustrated.

I claim.

The ornamental design for a water bottle or similar article, substantially as shown and described.
